UNITED STATES PATENT OFFICE

100,400

DESIGN FOR A TIRE

Harold L. van Doren, Toledo, Ohio, assignor to Wingfoot Corporation, Wilmington, Del., a corporation of Delaware

Application October 31, 1935, Serial No. 59,293

Term of patent 14 years

To all whom it may concern:

Be it known that I, Harold L. van Doren, a citizen of the United States, residing at 604 Winthrop Street, city of Toledo, county of Lucas, and State of Ohio, have invented a new, original, and ornamental Design for a Tire, of which the following is a specification, reference being had to the accompanying drawing, forming part thereof.

Fig. 1 is a perspective view of a tire with a sidewall portion in full lines showing my new design, and

Fig. 2 is a fragmentary cross-sectional view taken on the line 2—2 of Fig. 1.

I claim:

The ornamental design for a tire, as shown.

HAROLD L. VAN DOREN.
